HOLDER FOR A NAME PLATE PRISM OR THE LIKE

Leo R. Slaton, Chicago, Ill., assignor to Swiss Harmony,
Inc., Chicago, Ill., a corporation of Illinois

Filed Aug. 23, 1965, Ser. No. 86,675

Term of patent 7 years

(Cl. D1—3)

Fig. 1.

FIG. 1 is a front elevational view of a holder for a name plate prism or the like embodying my new design, as seen from a position along line 1—1 of FIG. 2;

FIG. 2 is a rear perspective view thereof, and

FIG. 3 is an end elevation of same.

I claim:

The ornamental design for a holder for a name plate prism or the like, substantially as shown.
